UNITED STATES PATENT OFFICE.

CHARLES W. SMITH, OF CLEVELAND, OHIO.

DESIGN FOR A PACKAGE-CARRIER.

SPECIFICATION forming part of Design No. 34,406, dated April 28, 1901.

Application filed August 24, 1899. Serial No. 728,373. Term of patent 14 years.

To all whom it may concern:

Be it known that I, CHARLES W. SMITH, a citizen of the United States, and a resident of Cleveland, county of Cuyahoga, and State 5 of Ohio, have invented and produced a new and original Design for a Package-Carrier, of which the following is a specification, reference being had to the accompanying drawings, forming a part thereof.

Figure I represents a perspective view of a bicycle package-carrier, showing my new design; and Fig. II represents a front elevation of same.

As shown in the drawings, the leading or 15 material feature of my design consists of the top, bottom, and rear portions *b*, *c*, and *d*, respectively, bent so as to form a continuously-curved surface, the top portion curving downward at the front and the bottom por-

tion curving upwardly at the front, such 20 downwardly and upwardly curving portions being joined by a front portion *e* of flat or plane surface formation. The lateral edges of such top, bottom, rear, and front portions of the receptacle each inclose a flat side portion *a* of a contour similar to that of said edge, thereby forming an inclosed receptacle having substantially the form of an Italic letter "a."

What I claim is—

The design for a bicycle package-carrier as herein shown and described.

Signed by me this 22d day of August, 1899.

CHARLES W. SMITH.

Attest:

JAMES W. MOORE,
A. E. MERKEL.
